MULTIPOLE SWITCH

Ralph D. Amsden, Lynn, Mass., assignor to General Electric Company, a corporation of New York

Application October 17, 1933, Serial No. 693,929

7 Claims. (Cl. 200—8)

My invention relates to multipole switches, and has for an object the provision of an inexpensive and reliable switch of this character.

Heretofore switches have been provided with hills and valleys for obtaining a snap action of the movable contacts. Much is yet to be desired, however, in providing multipole switches with a construction providing a snap action and for permitting the use of such switches in different types of circuits. Thus, for example, in a full wave rectifier it is desirable to adjust simultaneously the voltage across each of the rectifiers in order to control the voltage of the direct current circuit.

In carrying out my invention in one form thereof, I provide an insulating support provided with a plurality of ridges and depressions around the inner periphery thereof. A contact member is secured to each side of the support, each contact extending part way into the depression. A pair of movable contact members resiliently supported from a rotor formed of insulating material are arranged to be operated from one depression to the other with a snap action so that two circuits may be simultaneously completed by the resilient contact member. In the off position the resilient contact members jointly operate a movable contact to interrupt a line circuit.

For a more complete understanding of my invention reference should now be had to the accompanying drawing wherein I have shown in Fig. 1 a perspective view, partly in section, of my invention, whilst Fig. 2 illustrates diagrammatically my invention applied to a full wave rectifier circuit.

Referring to the drawing, I have shown my invention in one form as applied to a multipole switch 10 having a circular base 11 formed of insulating material. Around the inner periphery of the base are provided a plurality of hills or ridges 12 and a plurality of valleys or depressions 13. In the depression 13a there are mounted two stationary contacts 15 and 16, the contact 16 being secured to one side 18 of the base 11 by a screw 19. The contact 16 is formed by a conductor 20 having a contact portion 16 bent at an angle such that the screw 19 and the contact portion 16 rigidly secure the conductor 20 in a tangential direction with respect to the depression 13a. The contact 15 is similarly formed except that it extends in an opposite tangential direction so that the screw 22 lies between the contact 16 and the next adjacent contact 23, this construction being identical for the remaining contacts of the multiple switch. By reason of the opposite tangential relationship of the body portions of the contacts

a maximum amount of insulation is provided between them and their respective fastening screws. Two U-shaped movable contact members 25 and 26 are arranged to slidably engage an end portion 28 of a rotor 30 formed of insulating material and secured to a rotatable shaft 33. The end portion 28 is provided with channels 31 and 32 within which the legs of the U-shaped members 25 and 26 are slidably mounted. Since the movable contact members 25 and 26 are identical in construction only one contact, the contact 25 will be described in detail. The legs of the contact 25 are bent inwardly toward the channels and terminate in the outwardly extending legs 34 and 35 to which are secured the ends 36 and 37 of a resilient member 38. A screw 40 secures the resilient member 38 intermediate its ends to the rotor 30 at a point diametrically opposite to the end portion 28.

It will be understood that a suitable operating handle (not shown) is secured to the end of the shaft opposite the end 33 so that the rotor 30 can be moved either in a clockwise or a counter-clockwise direction. Assuming that the rotor 30 is moved in the clockwise direction, it will be observed that the ends of the movable contacts 25 and 26 strike against the ridge 12b causing the contact members to be moved radially along the channels 25 and 26 provided in the extension 28. There is also a certain amount of rotation imparted to the movable contact member with respect to the end portion 28, this rotation being permitted by a relatively loose fit between each contact member and its cooperating channels. As soon as the contact members pass slightly beyond the center of the ridge 12b the resilient springs release the energy stored therein and operate the movable contact members with a snap action into the depression 13b and in nesting relationship therewith, circuits being simultaneously completed thereby through the conductors 49 and 50.

If the clockwise rotation of the rotor 30 is continued the movable contact members 25 and 26 are moved onto a ridge 52 and finally are operated with a snap action against an insulating block forming a switch operating member 54 supported on a shaft 55. The switch member 54 is biased to the closed circuit position by a spring 56. The shaft 55 carries a movable contact 58 arranged to complete a circuit between a pair of stationary contacts 59 and 60. As soon however as the movable contact members 25 and 26 strike the switch member 54 the energy stored in the resilient members is sufficient to overcome the 110

bias of the spring 56 to open quickly the circuit thereby deenergizing the multipole switch.

Assuming now that the movable contact members 25 and 26 have been operated in a counter-clockwise direction into the depression 13e, it will be observed that further counterclockwise movement is prevented by a relatively high ridge 65. Consequently, it is necessary for the switch to be operated from the depression 13e 10 in a clockwise direction to deenergize the line circuit which is completed through the contacts 59 and 60.

Referring to Fig. 2, I have shown the switch 10 applied to a full wave rectifier set, the movable contact members 25 and 26 being connected respectively to cathodes 70 and 71 of the rectifier valves 72 and 73. The connections to each of the movable contact members are made by means of conductors 66 and 67. The conductor 66 is connected to a copper plate 68 through which the shaft 33 extends. A resilient conductor 69 secured by the screw 40 to the rotor 30 is biased into engagement with the plate 68. Similarly the contact 26 is connected to the plate 67a forming a terminal connection for the conductor 67 and providing a support for the shaft 33. The secondary windings 75 and 76 are connected together at their midpoints 77, each secondary being provided with a plurality of taps (not shown) each of which is connected to a contact member. Thus, for example, the secondary winding 75 has a plurality of taps connected to the contact members provided on one face of the insulating support 11 whilst the secondary winding 76 has its taps connected to the contact members provided on the opposite face of the support 11.

The primary winding 80 of the transformer 82 is connected in series with the contacts 59 and 60 40 across an alternating current supply line indicated by the supply lines 84 and 85. Whenever the switch is operated so that the rotor 30 brings the movable contacts 25 and 26 into engagement with the switch member 54 the rectifier set is 45 deenergized because of the opening of the circuit between the contacts 59 and 60.

Each valve 72 and 73 is provided with an anode 87 and 88, the anode 87 being connected in series with a fuse link 89, an ammeter 90, a reactor 91 50 and by conductor 92 to a direct current load circuit. Similarly, the anode 88 is connected in series circuit with a fuse link 94, an ammeter 95, a reactor 96 and to the conductor 92. The other side of the direct current load circuit is completed by conductor 97 connected to the midpoint 77 of the secondary coils of the transformer.

In order to control the voltage of the direct current circuit 92, 97 the switch 10 is operated so that the rotor 30, as viewed in Fig. 1, rotates 60 in a counterclockwise direction (the operating handle of course rotating in a clockwise direction). As the contact members 25 and 26 move from depression to depression with a snap action, the voltage across each of the rectifiers 65 72 and 73 is increased by an equal amount.

While I have shown a particular embodiment of my invention, it will be understood, of course, that I do not wish to be limited thereto since many modifications may be made, and I, therefore, contemplate by the appended claims to cover 70 any such modifications as fall within the true spirit and scope of my invention.

What I claim as new and desire to secure by Letters Patent of the United States, is:

75 1. A multipole switch, comprising a support

formed of insulating material, said support being provided with a plurality of depressions, a plurality of contacts on each side of said support each provided with an end portion and a body portion, said end portion of each contact extending into a corresponding one of said depressions and said body portions of the contacts on one side of said base extending tangentially in one direction from said depressions, and the body portions of the contacts on the other side of said support extending tangentially in an opposite direction from said depressions, fastening means for each body portion extending through said support, said opposite tangential relationship of said body portions permitting a maximum amount of insulation between said body portions and said fastening means, contact means arranged to nest within said depressions, resilient means for biasing said contact means into engagement with said end portions of said contacts, and means for producing relative motion between said contact means and said contacts, said resilient means permitting said contact members to move over the ridge between a pair of depressions and thereafter operating said contact members into a depression with a snap action.

2. A multipole switch, comprising a support formed of insulating material, said support being provided with a plurality of depressions, a second supporting member formed of insulating material and having an end portion arranged to move in parallel relation with said ridges and depressions, a U-shaped rigid contact member having its legs slidably engaging said second support, the ends of said U-shaped member being flared outwardly, resilient means secured to said outwardly flared ends and secured to said second supporting member at a point opposite said end portion for supporting and biasing said U-shaped member into a selected one of said depressions, and means for producing relative motion between said supports for operating said rigid contact member with a snap action from one to the other of said depressions.

3. A multipole switch, comprising a support formed of insulating material, said support being provided with a plurality of ridges, one or more contact members secured intermediate said ridges, a contact member, a movable switch member mounted between a pair of adjacent ridges for operating said contact member to an open circuit position, means for biasing said switch member and contact member to a closed circuit position, a second supporting member formed of insulating material and having an end portion arranged to move in parallel relation with said ridges, a rigid contact member slidably mounted on said second support, resilient members secured to said rigid contact and to said second support for biasing said rigid contact member to a circuit closing position against said first support, and means for producing relative motion between said first and second supports for operating said rigid contact member with a snap action from one circuit closing position to the other, said resilient member being arranged to operate said rigid contact member into engagement with said switch member with a snap action to quickly operate it to its open circuit position.

4. A multipole switch, comprising a cylindrical support formed of insulating material, said support being provided with a plurality of depressions on its inner periphery, a plurality of contact members partially extending into said depressions from one side of said support and a
